CAP FOR A WRITING INSTRUMENT

Clarence D. Zierhut, Granada Hills, and Walter Susumu Nakano, Los Angeles, Calif., assignors to The Gillette Company

Filed Apr. 20, 1973, Ser. No. 353,729

Term of patent 14 years

Int. Cl. D19—06

U.S. Cl. D19—57

Fig. 1.

Fig. 3.

Fig. 2.

FIG. 1 is an elevational view of a cap for a writing instrument showing our new design;

FIG. 2 is a top plan view; and

FIG. 3 is a perspective view.

The characteristic feature of our design resides in the narrow upstanding rim surrounding the depressed central area on a cap for a writing instrument of the configuration shown.

We claim:

The ornamental design for a cap for a writing instrument, as shown and described.
